UNITED STATES PATENT OFFICE

SAMUEL RUBEN, OF NEW YORK, N. Y., ASSIGNOR TO RUBEN PATENTS COMPANY, OF NEW ROCHELLE, NEW YORK, A CORPORATION OF DELAWARE

METHOD FOR GENERATING ELECTRICAL POTENTIAL

Application filed March 6, 1930. Serial No. 433,830.

This invention relates to a method for generating electrical potential, and more particularly it relates to such a method for the generation of potential directly from heat due to the combination of dissimilar materials without the use of mechanical or magnetic devices. The invention constitutes an improvement upon my invention described in my co-pending application filed September 17, 1929, bearing Serial Number 393,307, and has as an object the provision of a thermo-chemical method for generating potential with a high efficiency.

The present invention utilizes a principle of operation which is entirely novel; it employs the heat of formation of a compound between certain electro-positive materials and a relatively electro-negative material.

When certain alkali metals, such as potassium and sodium are placed in contact with a relatively electro-negative material, such as mercury, and an amalgam is so formed, a potential is generated at the point of contact, corresponding to the energy liberated by the reaction in forming the amalgam.

By the terms of my invention continuous current is generated by distilling an amalgam in one chamber in a vessel, partially condensing the vapors of distillation within a manifold and adjacent the vaporizing chamber, and in a different area condensing the uncondensed vapors and discharging those later condensed vapors in contact with a conductive body as a section of the manifold, into contact with a body containing alkali metal in another chamber and thereby forming a further amalgam, and carrying away heat of the amalgam reaction. A part of the conductive body is in juxtaposition to the amalgam in the second chamber, and, with the content of that chamber, is connected in an external electrical circuit. The newly formed amalgam is passed to the vaporizing chamber for re-vaporization, the method being thus carried on in a cycle. If the temperature at the vaporizing chamber is sufficiently high, with the electro-negative vapors a small amount of the alkali metal may be vaporized and carried up with a slight amount of amalgam into the mani-

fold connecting with the second or amalgamation chamber. To prevent this action, a partial cooling or condensation is effected by cooling plates provided about the connecting manifold just above the vaporizing chamber, so that the vapors of the alkali metal and any escaping amalgam are condensed before such passage and are forced to remain within the vaporizing chamber. Effecting the partial condensation just above the vaporizing chamber constitutes an important improvement upon the method described in my prior and co-pending application to which reference is hereinbefore made. While mercury is selected as a desirable material, other elements such as bismuth or their amalgams can be used satisfactorily. As the relatively electro-positive material, potassium has been found to be a very practicable element for this application; but other alkali metals such as rubidium, caesium, sodium, etc., can be used.

The invention may be best understood by reference to the following description of the accompanying drawing illustrating an embodiment thereof, showing a section view thereof in which 1 represents a highly evacuated vessel of refractory glass partially thermally insulated by covering 1_b, and containing in chamber 2, an amalgam of mercury and potassium 3. Air cooled plates 7, are employed as a rectifier means to condense any potassium vapor or amalgam that may have been carried over with the mercury due to the partial pressure of that material in the boiler chamber. These condensed materials are returned directly to the boiler, allowing the necessary pure mercury vapor to be carried over into condenser 7_a. The temperature maintained at the air cooled radiator 7, is of course, above the boiling temperature of the distilled mercury vapor. Above chamber 2, is manifold 5, which projects into metal tube 8, the lower end of which is tapered and has a small orifice at the bottom, close to the material in the second chamber. Surrounding and extending below tube 8, is chamber 2_a and, connecting chambers 2 and 2_a, are conduit 10 having a trap therein, 11, and lower conduit 12. Connecting with manifold 5, is inlet pipe 6, controlled by a valve for intro-

ducing the mercury amalgam and potassium. In chamber 2_a is a body of potassium or a weak amalgam 3_a, which is maintained at an approximate level with that of amalgam 3, in 5 chamber 2, by conduit 12. A cooling system 9, is placed about the lower portion of chamber 2_a. Tube 8 and potassium body 3_a, are used as terminals for connection in an external electric circuit. At 1_a is a nipple through 10 which vessel 1 is evacuated to as high a degree as is practicable previous to the operation of the apparatus.

As heat is applied to the mercury-potassium amalgam 3, in chamber 2, mercury, and 15 possibly a slight amount of potassium and amalgam, are distilled from the amalgam, passing through manifold 5. Any potassium vapors and amalgam are condensed by cooling plates 7, and precipitated back into chamber 2, the mercury vapor passing on through 20 the conduit. The temperature of the amalgam in condenser 7, is maintained above the vaporizing temperature of mercury. In the area surrounded by cooling element 7_a, the 25 mercury vapors are condensed, the metal flowing through metal tube 8, and its orifice to the top of potassium body 3_a, and there forming an amalgam with it. Some of the heat generated in the reaction forming the amalgam is carried off by cooling member 9, the 30 cooling fluid being applied only in sufficient quantity to dissipate the heat generated by the combination between the alkaline metal and the mercury. When the mercury flowing 35 out of the metal nozzle makes contact with the potassium or weak amalgam in chamber 2_a, an amalgamation of the metals is effected and a potential is there generated which is transmitted through the circuit comprising the precipitating metals, the metal 40 tube, the amalgam 3_a in the reaction chamber, and the external circuit represented by terminals 13 and 14.

The amalgam or reaction product formed in 45 chamber 2_a, raises the level of the liquid in that chamber so that it gravimetrically flows back through conduit 12 to boiler chamber 2. The temperature difference between the two amalgams also serves to promote the flow of 50 the newly formed amalgam to that in the heated chamber. Trap 11, serves to prevent the passage of vapor from chamber 3_a to chamber 2, and likewise serves to prevent the passage 55 of the product of distillation from chamber 2 to chamber 3_a. The exhaustion of the entire apparatus to the vapor pressure of the materials contained therein serves to maintain at a minimum the energy necessary for the vaporization of the materials. In some cases 60 it might be desirable to add an inert gas such as helium to assist in cooling. The temperature of the first condenser should not be brought to the point at which the potassium solidifies; it must be maintained in a liquid 65 state.

What I claim is:

1. The method of generating electrical potential which consists in discharging a stream of mercury into a body of potassium, the said stream and said body of potassium being connected in an external conductive circuit. 70

2. The method of generating electrical potential which consists in discharging a stream of mercury into a body of an alkali metal, the said stream and said body of alkali metal, being connected in an external conductive circuit. 75

3. The method of generating an electrical potential which consists in distilling an amalgam of mercury and an alkali metal, partially condensing the distilled vapors over the body of amalgam and precipitating the condensed material back to the body of amalgam, later condensing the uncondensed mercury vapor and precipitating the condensed mercury vapor to and amalgamating it with a body of alkali metal, carrying off heat generated by forming the amalgam, and passing the second mentioned amalgam into the first mentioned amalgam. 80

4. The method of generating an electrical potential which consists in distilling in an atmosphere containing an inert gas, an amalgam of mercury and an alkali metal, partially condensing the distilled vapors over the body of amalgam and precipitating the condensed material back to the body of amalgam, later condensing the uncondensed mercury vapor and precipitating the condensed mercury vapor to and amalgamating it with a body of alkali metal, carrying off heat generated by forming the amalgam, and passing the second mentioned amalgam into the first mentioned amalgam. 95

5. The method of generating electrical potential which consists in discharging a stream of mercury into a body of potassium in an atmosphere containing an inert gas, the said stream and said body of potassium being connected in an external conductive circuit. 105

6. The method of generating electrical potential which consists in discharging a stream of mercury into a body of an alkali metal in an atmosphere containing an inert gas, the said stream and said body of alkali metal 115 being connected in an external conductive circuit.

Signed at New York, in the county of New York and State of New York, this 3rd day of March, A. D. 1930.

SAMUEL RUBEN.
